UNITED STATES PATENT OFFICE

126,266

DESIGN FOR A FRAME FOR A TUMBLER RACK

Adolph J. Havlis, Oak Park, Ill., assignor to Key-
stone Metal Products Co., Chicago, Ill., a cor-
poration of Illinois

Application July 10, 1940, Serial No. 93,535

Term of patent 3½ years

To all whom it may concern:

Be it known that I, Adolph J. Havlis, a citizen
of the United States, residing at Oak Park, in
the county of Cook and State of Illinois, have
invented a new, original, and ornamental Design
for a Frame for a Tumbler Rack, of which the
following is a specification, reference being had
to the accompanying drawing, forming a part
thereof.

In the drawing:

Figure 1 is a front elevational view of a frame
for a tumbler rack, showing my design;

Figure 2 is an end elevational view of the
frame for a tumbler rack shown in Figure 1; and

Figure 3 is a top plan view of the frame for a
tumbler rack shown in Figure 1.

I claim:

The ornamental design for a frame for a tum-
bler rack, substantially as shown.

ADOLPH J. HAVLIS.
